E. S. STRAIT.

CAPE.

No. 15,310.

Patented Aug. 19, 1884.

UNITED STATES PATENT OFFICE.

E. SMITH STRAIT, OF TROY, NEW YORK.

DESIGN FOR A CAPE.

SPECIFICATION forming part of Design No. 15,310, dated August 19, 1884.

Application filed June 18, 1884. Term of patent 3½ years.

To all whom it may concern:

Be it known that I, E. SMITH STRAIT, of the city of Troy, county of Rensselaer, State of New York, have invented and produced a new and ornamental Design for Capes, of which the following is a specification.

My design relates to capes of an ornamental character; and it consists, as shown in the annexed illustration, of a cape having a collar, K, with a border, b', a body, B, having a bottom border, b², and an eagle, E, on the cape body at the back, in a position shown as poised and about to swoop.

Having thus described my design, what I claim, and desire to secure by Letters Patent, 15 is—

The design for a cape consisting of the body B, having a bottom border, b², a collar, K, with a border, b', and the back of the cape ornamented with an eagle, E, as shown and 20 described.

Signed at Troy, N. Y., this 16th day of June, 1884, and in the presence of the two witnesses whose names are hereto writ.

E. SMITH STRAIT.
